UNITED STATES PATENT OFFICE.

FRANK J. MATCHETTE, OF MILWAUKEE, WISCONSIN

VACUUM CLEANING-TOOL.

1,094,579.

Specification of Letters Patent. Patented Apr. 28, 1914.

Application filed May 2, 1910. Serial No. 558,888.

To all whom it may concern:

Be it known that I, FRANK J. MATCHETTE, a citizen of the United States, residing at Milwaukee, in the county of Milwaukee and State of Wisconsin, have invented certain new and useful Improvements in Vacuum Cleaning-Tools, of which the following is a specification, reference being had to the accompanying drawing, forming a part 10 thereof.

This invention relates to a vacuum cleaning tool of the type which are intended to be used for cleaning uncarpeted floors and other surfaces, and the objects of the invention are to provide a tool of such a shape that if it comes in contact with an object, such as a chair or table leg, etc., the tool instead of being stopped thereby, will be deflected sidewise and slide by the same, and 15 preferably the tool is so constructed that if it contacts with such an object it will slide by the same either toward the right or the left hand, and whether the tool is being moved in one direction or in the opposite direction, and to provide a tool which will 20 sweep the dirt sidewise into windrows opposite the air entrances into the tool.

Further objects of the invention are to improve tools of this type in the manner to 25 be more specifically pointed out in this specification.

Referring to the drawings which accompany this specification and form a part thereof, on which drawings the same reference characters are used to designate the 30 same elements wherever they may appear in each of the several views, and which drawings illustrate an embodiment of this invention, Figure 1 is a plan view of a 35 vacuum cleaning tool; Fig. 2 is a vertical section of the cleaning tool taken on the line *a*—*a*, Fig. 1; and Fig. 3 is a vertical section of the tool taken on the line *b*—*b*, Fig. 1.

Referring specifically to the drawings, the numeral 1 designates the body of the tool, which as seen in plan view, is approximately diamond-shaped and said body may be constructed of 40 any other suitable or preferred material. The body of the tool is provided with an aperture 2, extending therethrough, which is in communication with a slot 3 in the lower face of the body of the tool, and which extends transversely 45 of the body of the tool. The lower face of

the body of the tool or the face which contacts with the surface to be cleaned, as a floor, for example, is preferably covered with felt 4, or any other suitable or preferred polishing material, and this felt is 50 preferably in two separate pieces separated by a space 5, which registers with the slot 3 in the bottom of the body of the tool.

The numeral 6 designates a handle plate adapted to be secured by screws 7 to the top of the body 1 of the tool, and this plate 6 has an aperture 8 therein adapted to register with the aperture 2 in the body of the tool. Plate 7 is preferably made from metal and has upstanding lugs 9 and 10 provided 60 thereon which receive the trunnions 11 and 12 of the movable handle 13, so that said handle 13 can be raised and lowered with respect to the floor or the tool without restricting the passageway for the air from 65 slots 5 and 3 and aperture 2 into the hollow interior 14 of the handle 13, as clearly shown by Fig. 3 of the drawings.

By reference to Fig. 1 of the drawings, it will be noticed that the front and back ends of the tool 15 and 16 are sharply pointed except that at their extreme ends they are rounded slightly so as not to mar or disfigure objects with which the tool might come in contact, but the side points of the diamond 85 shape of the tool are omitted, the body of the tool being cut off at the sides so as to be substantially parallel with the handle 13, as clearly shown by Fig. 1 of the drawings, and the body of the tool is provided with 90 recesses 17 and 18, located in these parallel side portions and at the ends of slot 3, within which recesses brush members or bristles 19, 20, 21 and 22 are secured, preferably in two tiers, and project out of said 95 recesses and downwardly at an angle, as clearly shown by Figs. 1 and 2 of the drawings.

The diamond-shaped points are omitted from the sides of the tool so as to enable 100 the tool to more readily and easily slip by an object and remain in proximity thereto, and the recesses 17 and 18 are provided, so that the ends of the brushes or bristles 19, 20, 21 and 22, which are secured to the 105 body of the tool, may be secured to the body of the tool inside of the outline of the body thereof, so that the ends of the brushes or bristles which are fastened to the body of the tool cannot come in contact with an ob- 110

- ject, but only the outer ends of the brushes or bristles, so that said brushes or bristles can readily bend as the tool passes an object, without liability of their being broken.
- 5 This construction of the tool and brushes also permits the tool being used alongside of a mop board, for example, without danger of scarring the mop board and without danger of breaking the brushes or bristles.
- 10 It will be readily apparent from an inspection of Fig. 1 of the drawings that the tool will slide or dodge sidewise when it is either moving forward or back, if it strikes an object, and moreover, the obliquely disposed edges forming diamond-shaped ends of the tool tend to separate the dust and sweep it sidewise and pile it up in windrows at the sides of the tool, so that it is readily picked up *en masse* so to speak, when opposite the slot 3 and recesses 17 and 18 at the ends of said slot. If the tool had a straight front edge the dust and dirt would be rolled over and over and rubbed into the floor or surface being cleaned instead of being parted and swept into windrows, as is the case with a diamond-shaped tool of the character described, and with a tool of the character described, the felt face being of a considerable area, acts as a floor polisher, while the tool is being used in sweeping.
- 15 The bristles or brushes 19, 20, 21 and 22 not only provide for sweeping the dust out of corners and edges, around the legs of chairs, desks, tables, radiators, etc., but they also serve to provide definite channels for the air to enter the slot 3 so as to confine the inrushing air, thereby increasing the efficiency of the tool.
- 20 The lower edges of the tool are beveled to an angle of about 45° as shown, so that

the tool will ride up on to and over small obstructions such as uneven floor boards, etc.

What is claimed is:

1. A vacuum cleaning tool comprising a body provided with a recess in a side thereof and a slot in open communication with said recess and bristles or brushes secured to the body of said tool above said slot and extending outwardly and downwardly through said recess and outside the body of said tool.

2. A vacuum cleaning tool comprising a body provided with an open-ended slot in the under face thereof in open communication with the atmosphere at the sides of the tool, said body being also provided with floor-contacting, sweeping members, the outer edges of which are obliquely disposed with respect to the normal directions of movements of the tool to sweep dust and dirt sidewise from in front of the tool to the sides of the tool.

3. The combination in a vacuum cleaning tool of a body member provided with recesses in the sides thereof and a slot in open communication with said recesses on the under face of the tool, bristles or brushes secured to the body member above said slot and extending outwardly and downwardly through said recesses and outside of the tool, and sweeping and polishing members secured to the said body member, the said body member and sweeping and polishing members having their outer edges obliquely disposed with respect to the normal directions of movements of the tool.

In witness whereof I hereto affix my signature in presence of two witnesses.

FRANK J. MATCHETTE.
